(57) **CLAIM**

The ornamental design for a LED light fixture, as shown and described.

DESCRIPTION

FIG. 1 is a bottom perspective view of a LED light fixture showing the design;

FIG. 2 is a top perspective view thereof;

FIG. 3 is a bottom plan view thereof;

FIG. 4 is a top plan view thereof;

FIG. 5 is a front elevation view thereof, the rear elevation view being a mirror image of the front;

FIG. 6 is a bottom perspective view of another embodiment of a LED light fixture showing the design;

FIG. 7 is a top perspective view thereof;

FIG. 8 is a bottom plan view thereof;

FIG. 9 is a top plan view thereof; and,

FIG. 10 is a front elevation view thereof, the rear elevation view being a mirror image of the front.

The portions of the LED light fixture shown in broken lines form no part of the claimed design.
